The ornamental design for a three seal sachet with a front face fitment, as shown and described.

DESCRIPTION

FIG. 1 is a perspective view of the three seal sachet with a front face fitment showing our new design;

FIG. 2 is a top plan view thereof;

FIG. 3 is a bottom plan view thereof;

FIG. 4 is a right side elevational view, the left side elevational view being a mirror image thereof;

FIG. 5 is a front elevational view thereof; and,

FIG. 6 a rear elevational view thereof.
